UNITED STATES PATENT OFFICE.

JOSEPH A. GOODWIN, OF BERKLEY, VIRGINIA.

FLYING-MACHINE.

1,019,782.

Specification of Letters Patent. Patented Mar. 12, 1912.

Application filed June 28, 1911. Serial No. 635,710.

To all whom it may concern:

Be it known that I, JOSEPH A. GOODWIN, a citizen of the United States, residing at Berkley, in the county of Norfolk and State 5 of Virginia, have invented certain new and useful Improvements in Flying-Machines, of which the following is a specification.

My invention relates to improvements in flying machines, and more particularly to 10 improved supporting and stabilizing means for aeroplanes, the object of the invention being to provide planes or wings of a shape, and positioned at an angle, to exert maximum sustaining action of the wings on the 15 air, and resembling in their utility, the wings of a bird in soaring flight.

A further object is to provide improved means for automatically or manually changing the angle of the wings or planes.

20 A further object is to provide a flying machine having wings or planes secured to the fore-and-aft frame of the machine, and located at an angle to the fore-and-aft frame, extending forwardly and upwardly, and 25 curving or bending at opposite angles at its respective ends, said angles gradually changing to a central point between the ends of the wings where said wings are approximately straight.

30 With these and other objects in view, the invention consists in certain novel features of construction and combinations and arrangements of parts, as will be more fully hereinafter described and pointed out in the 35 claims.

In the accompanying drawings: Figure 1, is a view in front elevation illustrating my improvements. Fig. 2, is an enlarged view in transverse section through the forward 40 part of the machine at the center thereof. Fig. 3, is a plan view of the framework of one of the wings. Fig. 4, is an enlarged view in longitudinal section through the center of the machine. Fig. 5, is a top plan 45 view. Fig. 6, is an enlarged view in section on the line 6—6 of Fig. 5. Fig. 7, is an enlarged view in section on the line 7—7 of Fig. 5. Fig. 8, is a view in side elevation.

50 1, represents the fore-and-aft frame of my improved machine, which I have illustrated in part only, the rear end of the frame being eliminated because such structure forms no part of the present invention, and may be varied to suit the trade.

55 2, 2, are my improved wings or planes which are composed of framework 3, illus-

trated in Fig. 3, and are secured at their inner ends to the fore-and-aft frame 1. These wings 2 incline upwardly and forwardly from their inner to their outer ends, and 60 their angle fore-and-aft changes from its inner end to its outer end, said angles being most clearly shown in Figs. 6 and 7.

The section 7, 7, illustrates the angle of the outer ends of the wings with the forward edge higher than the rear edge, and gradually inclining downward after curving upward slightly at the forward edge. Line 6—6 shows the shape of the wing at 70 the inner end, where it is lowest at its forward edge, and inclines upwardly.

The wings are preferably composed of the framework 3 covered by canvas as shown, and as commonly constructed, and these wings are shaped so that they assume the 75 opposite angles at their opposite ends, and gradually change their angles to an intermediate point where the wings are approximately straight. This is following out the plan of giving the greatest lifting force to 80 the outer ends of the wings, and gradually changing such angle to the inner ends where this lifting tendency is somewhat overcome to secure the proper equilibrium.

As the outer end of the wings are forwardly, they first take the air, and the inner ends follow, and by reason of the particular angles or approximately the particular angles, the wings attain the maximum of 85 lifting and sustaining quality on the air.

The forward edges of the wings are braced above and below by stay wires, so that they are held perfectly rigid. The upper wires 5 connect to an upwardly projecting frame 6, and the lower wires to a downwardly projecting frame 7 as clearly shown in Fig. 1. The rear edges of the planes are not so 90 braced, but are free to move within certain limits, and this movement of the rear edges 95 of the planes is controlled as will now be described.

A downwardly projecting forked standard 8 is secured to the fore-and-aft frame 1, and supports a longitudinally positioned shaft 9. A sprocket wheel 10 is secured on this 100 shaft in the forked end of the standard 8, and the teeth engage a sprocket chain 11. This sprocket chain 11 is connected by coiled springs 12 with wires 13, and the outer ends of these wires 13 are secured to 105 the wings 2, 2, adjacent the outer ends, and rear edges of the latter, or in other words, at 110

some point beyond the center of said wings. These wires 13, springs 12, and chain 11 compel the wings to tilt in opposite directions, so that the machine will automatically 5 stabilize, and this movement is cushioned by the springs, so that there will be no shock or sudden variation in the disposition of the wings. To further cushion this movement, a cross bar 14 is secured to shaft 9, and is 10 connected by wires 15 with coiled springs 16, said springs 16 secured to the bottom of fore-and-aft frame 1.

To manually change the angle of the wings, I provide a drum 17 which is operated by a hand wheel 18 located a convenient 15 distance from the operator's seat 19.

A wire 20 is secured at one end to bar 14, is then coiled around drum 17, and secured at its other end to the other end of bar 14, 20 and pulleys 21 are provided in the frame 1 over which said wire 20 passes, so as to reduce friction and properly position the several parts as seen most clearly in Fig. 4. It will therefore be noted that the operator 25 on seat 19 may turn hand wheel 18, and through the medium of the parts above described, change the angle of disposition of the wings. It will therefore be noted that my improved machine is equipped with 30 wings or planes which are set at an angle, and project forwardly and upwardly from their inner to their outer ends, therefore advancing the outer ends, and said outer ends given a greater angle to the line of flight 35 than the inner ends which are to their rear.

In other words, the outer ends of the wings which are advanced, and are forward and upward relative to the inner ends are set at an angle of incidence to the line of flight, so 40 as to catch a greater amount of air than the end which is lower and to the rear.

While the steering wheel is capable of controlling the movement of the machine to a certain extent, it has a wider range of usefulness than this. It enables the operator to 45 manually control the angles of the wings to maintain an equilibrium, and it also enables him to change the angle of one wing to offset a torn or broken wing. Therefore in the event that the equilibrium cannot be automatically maintained, it can be manually 50 maintained by means of the steering wheel.

Various slight changes might be made in the general form and arrangement of parts 55 described without departing from my invention, and hence I do not limit myself to the precise details set forth, but consider myself at liberty to make such changes and alterations as fairly fall within the spirit and 60 scope of the appended claims.

Having thus described my invention, what I claim as new and desire to secure by Letters Patent is:

1. In a flying machine, the combination 65 with a fore-and-aft frame, of wings secured

to the fore-and-aft frame and extending forwardly and upwardly from their inner to their outer ends, and at their outer ends positioned at a greater angle to the line of flight than at their inner, substantially as 70 described.

2. In a flying machine, the combination with a fore-and-aft frame, of flexible wings secured at their inner ends to the fore-and-aft frame, and extending upwardly and forwardly from their inner to their outer ends, 75 said wings positioned in a line, fore-and-aft, at a greater angle to the line of flight, at their outer ends, than at their inner ends, substantially as described.

3. In a flying machine, the combination with a fore-and-aft frame, of wings secured to the fore-and-aft frame and extending forwardly and upwardly from their inner to their outer ends, and at their outer ends positioned at a greater angle to the line of flight than at their inner, and means connecting the respective wings and constructed to change said angles of the wings, substantially as described.

4. In a flying machine, the combination with a fore-and-aft frame, of flexible wings secured at their inner ends to the fore-and-aft frame, and extending upwardly and forwardly from their inner to their outer ends, 95 said wings positioned in a line, fore-and-aft, at a greater angle to the line of flight, at their outer ends, than at their inner ends, and means connecting the respective wings and constructed to change said angles of the wings, substantially as described.

5. In a flying machine, the combination with a fore-and-aft frame, of wings secured to the fore-and-aft frame, and extending forwardly and upwardly, the outer end of each wing having its forward edge higher than its rear edge, and the inner end of each wing having its forward edge lower than its rear edge, substantially as described.

6. In a flying machine, the combination with a fore-and-aft frame, of wings secured to the fore-and-aft frame, and extending forwardly and upwardly, the outer end of each wing having its forward edge higher than its rear edge, and the inner end of each wing having its forward edge lower than its rear edge, a downwardly projecting standard secured to said fore-and-aft frame, a sprocket wheel mounted in said standard, a sprocket chain engaging the teeth of said sprocket wheel, wires secured to the outer rear portions of said planes, and springs connecting said wires and said chain, substantially as described.

7. In a flying machine, the combination with a fore-and-aft frame, of wings secured to the fore-and-aft frame, and extending forwardly and upwardly, the outer end of each wing having its forward edge higher than its rear edge, and the inner end of each 125

- wing having its forward edge lower than its rear edge, a downwardly projecting standard secured to the fore-and-aft frame, a shaft in said standard a sprocket wheel on said shaft, a sprocket chain engaging said sprocket wheel, wires secured to the outer rear portions of said wings, coiled springs connecting said wires and chain, a cross bar secured to said shaft, springs secured to the under face of the fore-and-aft frame, and wires connecting said last-mentioned springs with said cross bar, substantially as described.

8. In a flying machine, the combination with a fore-and-aft frame, of wings secured to the fore-and-aft frame, and extending forwardly and upwardly, the outer end of each wing having its forward edge higher than its rear edge, and the inner end of each wing having its forward edge lower than its rear edge, a downwardly projecting standard secured to the fore-and-aft frame, a shaft in said standard, a sprocket wheel on said shaft, a sprocket chain engaging said sprocket wheel, wires secured to the outer rear portions of said wings, coiled springs connecting said wires and chain, a cross bar secured to said shaft, a steering drum, a flexible connecting device wound on said drum and connected at its ends to said cross bar, and a steering wheel secured to turn with said drum, substantially as described.

9. In a flying machine, the combination with a fore-and-aft frame, of wings secured to the fore-and-aft frame, and extending forwardly and upwardly, the outer end of each wing having its forward edge higher than its rear edge, and the inner end of each wing having its forward edge lower than its rear edge, a downwardly projecting standard secured to the fore-and-aft frame, a shaft in said standard, a sprocket wheel on said shaft, a sprocket chain engaging said sprocket wheel, wires secured to the outer rear portions of said wings, coiled springs connecting said wires and chain, a cross bar secured to said shaft, a steering drum, a flexible connecting device wound on said drum and connected at its ends to said cross bar, a steering wheel secured to turn with said drum, springs secured to the under face of the fore-and-aft frame, and wires connecting said last-mentioned springs with said cross bar, substantially as described.

10. In a flying machine, the combination with a fore-and-aft frame, of wings secured to the fore-and-aft frame and extending forwardly and upwardly from their inner to their outer ends, and at their outer ends positioned at a greater angle to the line of flight than at their inner, upwardly and downwardly projecting frames secured to the fore-and-aft frame, and stay wires connecting said upwardly and downwardly projecting frames with the forward edges of said wings adjacent their outer ends, whereby the forward edges of said wings are maintained rigid, substantially as described.

11. In a flying machine, the combination with a fore-and-aft frame, of flexible wings secured at their inner ends to the fore-and-aft frame, and extending upwardly and forwardly from their inner to their outer ends, said wings positioned in a line, fore-and-aft, at a greater angle to the line of flight, at their outer ends, than at their inner ends, upwardly and downwardly projecting frames secured to the fore-and-aft frame, and stay wires connecting said upwardly and downwardly projecting frames with the forward edges of said wings adjacent their outer ends, whereby the forward edges of said wings are maintained rigid, substantially as described.

12. In a flying machine, the combination with a fore-and-aft frame, of wings secured to the fore-and-aft frame and extending forwardly and upwardly from their inner to their outer ends, and at their outer ends positioned at a greater angle to the line of flight than at their inner, and means connecting the respective wings and constructed to change said angles of the wings, upwardly and downwardly projecting frames secured to the fore-and-aft frame, and stay wires connecting said upwardly and downwardly projecting frames with the forward edges of said wings adjacent their outer ends, whereby the forward edges of said wings are maintained rigid, substantially as described.

13. In a flying machine, the combination with a fore-and-aft frame, of flexible wings secured at their inner ends to the fore-and-aft frame, and extending upwardly and forwardly from their inner to their outer ends, said wings positioned in a line, fore-and-aft, at a greater angle to the line of flight, at their outer ends, than at their inner ends, and means connecting the respective wings and constructed to change said angles of the wings, upwardly and downwardly projecting frames secured to the fore-and-aft frame, and stay wires connecting said upwardly and downwardly projecting frames with the forward edges of said wings adjacent their outer ends, whereby the forward edges of said wings are maintained rigid, substantially as described.

14. In a flying machine, the combination with a fore-and-aft frame, of wings secured to the fore-and-aft frame, and extending forwardly and upwardly, the outer end of each wing having its forward edge higher than its rear edge, and the inner end of each wing having its forward edge lower than its rear edge, upwardly and downwardly projecting frames secured to the fore-and-aft frame, and stay wires connecting said upwardly and downwardly projecting frames with the forward edges of said wings adjacent their outer ends, whereby the forward edges of said wings are maintained rigid, substantially as described.

frames with the forward edges of said wings adjacent their outer ends, whereby the forward edges of said wings are maintained rigid, substantially as described.

5 15. In a flying machine, the combination with a fore-and-aft frame, of wings secured to the fore-and-aft frame, and extending forwardly and upwardly, the outer end of each wing having its forward edge higher than 10 its rear edge, and the inner end of each wing having its forward edge lower than its rear edge, a downwardly projecting standard secured to said fore-and-aft frame, a sprocket wheel mounted in said standard, a sprocket 15 chain engaging the teeth of said sprocket wheel, wires secured to the outer rear portions of said planes, springs connecting said wires and said chain, upwardly and downwardly projecting frames secured to the 20 fore-and-aft frame, and stay wires connecting said upwardly and downwardly projecting frames with the forward edges of said wings adjacent their outer ends, whereby the forward edges of said wings are maintained rigid, 25 substantially as described.

16. In a flying machine, the combination with a fore-and-aft frame, of wings secured to the fore-and-aft frame, and extending forwardly and upwardly, the outer end of 30 each wing having its forward edge higher than its rear edge, and the inner end of each wing having its forward edge lower than its rear edge, a downwardly projecting standard secured to the fore-and-aft frame, a 35 shaft in said standard, a sprocket wheel on said shaft, a sprocket chain engaging said sprocket wheel, wires secured to the outer rear portions of said wings, coiled springs connecting said wires and chain, a cross bar 40 secured to said shaft, springs secured to the under face of the fore-and-aft frame, wires connecting said last-mentioned springs with said cross bar, upwardly and downwardly projecting frames secured to the fore-and- 45 aft frame, and stay wires connecting said upwardly and downwardly projecting frames with the forward edges of said wings, adjacent their outer ends, whereby the forward edges of said wings are maintained 50 rigid, substantially as described.

17. In a flying machine, the combination with a fore-and-aft frame, of wings secured to the fore-and-aft frame, and extending forwardly and upwardly, the outer end of 55 each wing having its forward edge higher than its rear edge, and the inner end of each

wing having its forward edge lower than its rear edge, a downwardly projecting standard secured to the fore-and-aft frame, a shaft in said standard, a sprocket wheel on 60 said shaft, a sprocket chain engaging said sprocket wheel, wires secured to the outer rear portions of said wings, coiled springs connecting said wires and chain, a cross bar secured to said shaft, a steering drum, a 65 flexible connecting device wound on said drum and connected at its ends to said cross bar, a steering wheel secured to turn with said drum, upwardly and downwardly projecting frames secured to the fore-and-aft 70 frame, and stay wires connecting said upwardly and downwardly projecting frames with the forward edges of said wings adjacent their outer ends, whereby the forward edges of said wings are maintained rigid, 75 substantially as described.

18. In a flying machine, the combination with a fore-and-aft frame, of wings secured to the fore-and-aft frame, and extending forwardly and upwardly, the outer end of each wing having its forward edge higher than its rear edge, and the inner end of each wing having its forward edge lower than its rear edge, a downwardly projecting standard secured to the fore-and-aft frame, a 80 shaft in said standard, a sprocket wheel on said shaft, a sprocket chain engaging said sprocket wheel, wires secured to the outer rear portions of said wings, coiled springs connecting said wires and chain, a cross bar 85 secured to said shaft, a steering drum, a flexible connecting device wound on said drum and connected at its ends to said cross bar, a steering wheel secured to turn with said drum, springs secured to the under face 90 of the fore-and-aft frame, wires connecting said last-mentioned springs with said cross bar, upwardly and downwardly projecting frames secured to the fore-and-aft frame, and stay wires connecting said upwardly 95 and downwardly projecting frames with the forward edges of said wings adjacent their outer ends, whereby the forward edges of said wings are maintained rigid, substantially as described.

In testimony whereof I have signed my name to this specification in the presence of two subscribing witnesses.

JOSEPH A. GOODWIN.
